WRITING INSTRUMENT
Frank T. Jolmann, 49 Hampton Drive,
Berkeley Heights, N.J.
Filed Nov. 9, 1961, Ser. No. 151,315
8 Claims. (Cl. 120—42.03)

This invention relates to a writing instrument having a retractable writing point. Particularly, this invention relates to a ballpoint pen having a side actuated retraction-protraction mechanism, e.g. a clip-actuated mechanism whereby depressing and releasing the clip retracts and protracts the ballpoint.

Recently several clip actuated writing instruments have become known, where the clip both retracts and protracts the point, e.g. U.S. Patents 2,881,736 and 2,988,055. In the first of these patents, the clip is pivotally mounted on the instrument casing so that it can rock. By depressing the lower portion of the clip into the casing, the writing point is projected, while depressing the upper portion of the clip into the casing retracts the writing point. Thus, this device requires application of pressure at different points on the clip to retract and protract. The second patent describes a clip, wherein pressure is applied to move the clip as a whole, into the casing to project or retract the writing point. However, this latter device requires careful control by the user in manipulation of the clip in order to achieve the desired result and therefore is not positively operating.

The present invention includes a clip-actuated device which is positively operating and can be actuated by pressing the clip into the casing until it meets a fixed stop. Pressure can always be applied to the same part of the clip to both retract and project the point. This eliminates possibility of confusion or necessity for remembering what portion of the clip needs to be pressed, since the same portion can always be pressed. In this way, it is not necessary to press different portions of the clip to retract or project the point. Furthermore, no particular manipulation of the clip is required other than depressing it into the casing and then releasing it.

In addition to the above advantages, the clip-actuated mechanism of the invention can be readily combined with a tip-actuated mechanism, as well as still other types of action mechanisms such as a conventional pushbutton action. The aforesaid tip-actuated mechanisms have recently become known and operate by pressing the writing tip end of the instrument into contact with a rigid surface, and then releasing from said contact to thereby either retract or protract the writing point. These tip-actuated instruments are very convenient to operate and can generally be operated while holding the instrument in the hand in a writing position. In addition, tip-action instruments generally have a spring loaded writing point which tends to cushion the writing point for easier writing. However, there are slight disadvantages with tip-action instruments. For example, they generally require a rigid surface for operation, which may not always be readily available. Also, they frequently result in the formation of dots during their actuation, which may sometimes be objectionable. By combining the previous described side or clip action with a tip-action, a single instrument can be provided which has the advantages of both types of action and satisfies individual preferences for these types of action in a single writing instrument. In other words, some consumers may prefer a tip-action mechanism, while others may prefer a side clip action. By combining both types of actions in a single instrument, both types of consumers can be satisfied with a single model. One main advantage of both tip-action and clip-action mechanisms is that a more streamlined appearance

2

can be given to the writing instrument since no pushbutton need project through the top of the instrument. However, as will be later demonstrated, the clip-action of the invention can also be readily combined with a top pushbutton action.

5 The above and other advantages and aspects of the invention will be further understood by the following descriptions and drawings which include a preferred embodiment of the invention. In the drawings:

10 FIGURE 1 is a longitudinal view, partly in section of a combined clip and tip-actuated ballpoint pen having its point in a point retracted position.

15 FIGURE 2 is a longitudinal view, partly in section, of the instrument of FIGURE 1, showing the clip in a depressed position during actuation of the retraction-protract mechanism.

20 FIGURE 3 is a longitudinal view, partly in section, of the instrument of FIGURES 1 and 2 showing the instrument in a point protracted position ready for writing.

25 FIGURE 4 is a cross-sectional view taken along the lines 4—4 of FIGURE 1.

FIGURE 5 is a schematic diagram, illustrating the operation of the retraction-protraction mechanism and wherein the tubular latching members of said mechanism have been developed into a single plane.

30 FIGURE 6 is a longitudinal view, partly in section, of another embodiment of the invention where the clip is pivoted at its upper end.

FIGURE 7 is a cross-sectional view taken along the lines 7—7 of FIGURE 6.

35 FIGURE 8 is a cross-sectional view taken along the lines 8—8 of FIGURE 6.

FIGURE 9 is a longitudinal view, partly in section, of another embodiment of my invention which is clip-actuated and pushbutton actuated.

40 FIGURE 10 is a longitudinal view, partly in section, of the embodiment of FIGURE 9 in a point protracted position.

FIGURE 11 is a cross-sectional view taken along the lines 11—11 of FIGURE 9.

45 FIGURE 12 is a cross-sectional view taken along the lines 12—12 of FIGURE 9.

FIGURE 13 is an enlarged fragmentary view of the latch receiving means of the embodiment of FIGURES 9 to 12.

50 FIGURE 14 is an enlarged fragmentary view of the latch means of the embodiment of FIGURES 9 to 12.

FIGURE 15 is a longitudinal view, partly in section of a modification of the instrument of FIGURES 9 to 15, which has no pushbutton and wherein the clip remains partly recessed within the casing when the writing point is projected.

55 FIG. 16 is a cross-sectional view taken along line 16—16 of FIG. 15.

Reference is now made to the embodiment of FIGURES 1 to 5. Here, the casing includes the main upper and lower tubular barrel sections 20 and 21, respectively, joined together by threaded engagement with the threaded tubular plug 22. The bore passing through the tubular section 21 is reduced in cross-section at 23 to thereby form the interior annular lip 24. A tubular hood 25, mounted for longitudinal movement within said reduced bore 23, is formed with an annular flange 26 at its inner end, while its outer portion 27 is tapered inwardly. The tubular hood 25, is formed internally with an annular lip 28.

60 A point and cartridge unit 29, includes the flange or flattened portion 30, and has the short terminal feed tube 31 which defines the annular shoulder 32. A writing ball 33 is carried at the outer end of said tube 31. Carried by the unit 29, is a tubular sleeve unit 34, whose upper end forms an interior annular shoulder 35. The

shoulder 35 is in abutting engagement with the upper end of said cartridge unit 29, while the air vent 47 admits air to the interior of said cartridge unit. The tubular sleeve unit 34 is externally formed with an annular groove 36 which carries a locking ball or pawl 37. Longitudinally movable within the upper barrel section 20 is the tubular sleeve 38 having a closed upper end 39. Projecting upwardly from said end 39, and integral therewith is the actuating member 40 having a beveled edge 41 proximate its upper end 42. Fixed within said tubular sleeve 38 are the tubular latch or ratchet members 43 and 44, which together define an annular cam surface. A relatively strong coil compression spring 45 has its upper end seating against the lower latch member 44 while its lower end seats atop the annular flange 46 defined by the lower end of the member 34. A second coil compression spring 67 is disposed between flanges 26 and 30. The spring 67 urges the cartridge unit 29 upwardly into engagement against the shoulder 35, while urging the hood 25 downwardly so that its flange 26 normally seats against the lip 24.

The upper tubular latch member 43 is formed with the downwardly projecting teeth 48 and 49, while the lower tubular latch member 44 is formed with the upwardly projecting teeth 50 and 51 (see FIGURE 5). The latch ball 37 is movable within said groove 36 around the longitudinal axis of the instrument, being retained between the cylinder 34 and the sleeve 38, while its longitudinal movement is limited by engagement with said teeth 48 to 51, inclusive.

The upper end of the instrument is closed by the cap 52 having the closed end 53, and the downwardly extending cylindrical portion 54 which defines the annular flange 55. The cap 52 is fixed, as by cementing to the casing section 20. A slot 60 extends through one side of said cylindrical portion 54. A pocket clip is transversely movable within said slot 60. Said clip has a springy leg portion 57, the lower cloth gripping end 58, and terminates at its upper end in the guide portion 59 which extends through the slot 60 defined by said cap 52 and the slotted upper end of the barrel member 20. The inner portion 61, of said guide portion 59, is longer than the length of said slot 60, to thereby form a flange which limits the outward movement of said clip unit in the assembled position of FIGURE 1. The upper edge 62 of the portion 61 is flat and rides against the flat underside 63 of said cap 52. The lower edge 64, of said portion 61, is beveled for sliding engagement against the complementary beveled edge 41.

The protraction-retraction mechanism operates upon relative longitudinal movement of the pawl or ball 37 and the ratchet latch members 43 and 44. This longitudinal movement can be obtained by depression of the clip into the casing and then releasing said clip, or by pressing the writing tip end of the instrument into contact with a rigid surface, followed by releasing said tip end from said contact.

The operation of the instrument will now be described, including reference to the schematic diagram of FIGURE 5. In FIGURE 5, the latch members 43 and 44 have been enlarged and developed into a single plane. The small circles enclosing numerals represent the various positions of the latch ball 37 relative to said latch members 43 and 44 at various stages of the retraction-protraction cycle.

Position 1 of FIGURE 5, i.e. the circle enclosing the numeral 1, represents the location of the latch ball 37 relative to the latch members 43 and 44 when the instrument is in the point retracted position of FIGURE 1. To project the writing point 33 from its retracted position of FIGURE 1 by tip-action, the lower writing portion of the instrument is pressed downwardly against a rigid surface 66 to force the hood 25, and then the point 33, inwardly relative to the casing against the pressure springs 45 and 67. This inward movement of the point

33 carries upwardly the member 34 with its latch ball 37. The latch members 43 and 44, meanwhile, cannot move upwardly because of the engagement of the end 42 against the inner wall 63 of the cap 52. The ball 37 will therefore come into engagement with the side of tooth 48, position 2 of FIGURE 5, and then move to position 3. Then, the writing tip end of the instrument is lifted from contact with said rigid surface 66. The hood 25 will return to its outwardly extending position under influence of spring 67, while the locking ball 37 will move to position 4 and then to position 5 under influence of spring 45. The main strong spring 45 will now be in an expanded position forcing the cartridge unit 29 to a point projected position against the weaker pressure of spring 67. The entire instrument will then assume the position of FIGURE 3. To retract the point 33 from its position of FIGURE 3 by tip-action, the point 33, and then the hood 25 are again pressed downwardly into contact with a rigid surface. By this action, the cartridge unit 29, with its sleeve 34 and the locking ball 37, will be moved upwardly relative to the barrel and members 43 and 44. Upon this relative upward movement, the ball 37 will move to position 6 where it engages a side of tooth 49, and will then roll to position 7. Upon lifting the writing instrument from the contacting rigid surface, the ballpoint cartridge 29, the sleeve 34 and latch ball 37, will all move downwardly relative to the casing under influence of coil spring 45. As this downward movement continues, the ball 37 will soon engage the side of tooth 51 (position 8) and will then roll to the position 1' of the schematic diagram of FIGURE 5. The position 1' is the same as position 1. The hood 25, will in the meantime be returned to its outwardly extending position and the entire instrument will again assume the position of FIGURE 1.

Protraction and retraction of the writing ballpoint 33 can also be obtained by pressing and releasing the clip. Thus, starting from FIGURE 1, the clip unit is pressed directly into the casing as far as it will go as illustrated by FIGURE 2. By this inward movement, the beveled edge 64 of the clip unit will exert a wedging action on the beveled edge 41 of the member 40. Because of this wedging action, the member 40 is driven downwardly relative to the casing. The sleeve 38, integral with the member 40, and said sleeve's fixed latch members 43 and 44 are thus forced downwardly relative to the casing and cartridge unit 29, against the pressure of springs 45 and 67. The cartridge unit 29, along with the member 34, also initially moves downwardly with the sleeve 38, but then becomes longitudinally stationary (although the ball 34 can rotate) when the cartridge shoulder 32 seats against the lip 28 of the hood 25 whose flange 26 in turn seats against lip 24. As the sleeve 38, and latch members 43 and 44 continue their downward movement, the member 44 drops out of contact with ball 37. Next, the tapered side of tooth 48 of member 43 will engage ball 37 and exert a wedging force on said ball to thereby move said ball into engagement against the side of tooth 49. Inward pressure on the clip is then released. The springs 45 and 67 will return the sleeve 38 and its fixed members 43 and 44 to their original positions of FIGURE 1. As this happens, the ball 37 will be wedged to a position relative to the members 43 and 44 corresponding to position 5 of FIGURE 5. The spring 67 will always maintain the cartridge unit 29 in engagement with the shoulder 35 of said sleeve 34. As the sleeve 38 moves to its original position of FIGURE 1, its integral upwardly extending member 40 will wedge the clip unit to its original position due to the sliding engagement of beveled surfaces 41 and 64. The entire instrument will thus assume the point protracted writing position of FIGURE 3.

Upon again depressing the clip unit into the casing as far as it will move, the member 40 will again be driven downwardly. The latch members 43 and 44 will thereby

again move downwardly relative to the cartridge unit 29 and the locking ball 37. The locking ball 37 will be wedged by contact with the beveled edge of tooth 49 (FIGURE 5) to a relative position corresponding to position 7 of FIGURE 5. Pressure is then released from the clip whereupon the clip will move to its outwardly extending position, as the members 40, 38, 43 and 44 all move upwardly under pressure of spring 45. During this upward movement, the latch ball 37 will be engaged by the tapered side of tooth 51 and finally wedged to a position corresponding to 1' of FIGURE 5. This position 1' is the same as position 1 so the entire instrument is now back in the position of FIGURE 1.

The embodiment of FIGURES 1 to 5 is readily assembled. While the assembly of the instrument is believed clear, there are several areas that might be further clarified. For example, the spring 45 is placed over the sleeve 34 so that the lower end of said spring rests on the flange 46. Then, the latch member 44 is placed around the sleeve 34 and pressed down, so as to compress the spring 45 and expose the groove 36. The latch ball 37 is then placed in the groove 36 whereupon the latch member 44 can be released. The spring 45 will then expand sufficiently so as to maintain the latch ball 37 against a side of a tooth of the member 44. The members 43 and 44 can then be fixed, e.g. by cementing, within sleeve 38.

Another embodiment of my invention is illustrated by FIGURES 6 to 8. Here, the clip 70 is a single integral member having the outer portion 71, and the inner portion 72 terminating in the beveled end 73. The cap 74 includes the downwardly extending tubular portion 75 fixed within the upper barrel section 76. A slot 77 extends through one side of said portion 75 and said barrel section 76. The clip 70 is pivotally held in position by the arcuate lip 78 extending downwardly from the cap 74 into the notch 79 formed in the clip 70, and the arcuate portion 80 of the upper barrel portion 76 which abuts the lower side 81 of said clip.

The writing unit 29' abuts the lower end 82 of the tubular sleeve member 83. An aperture 84 vents said writing unit 29'. Fixed within said sleeve member 83, are the tubular ratchet latch elements 44' and 43'. Longitudinally movable within said tubular elements 44' and 43' is the actuating cylinder 85 defining annular groove 86 carrying the latch ball 37'. The upper end of cylinder 85 is integral with the larger diameter cylinder 87 which is formed to define a wedge shaped surface 88. A groove 89 in said surface 88, receives the lower beveled inner end 73 of the clip 70. The cylinder 87 includes the upwardly extending member 90, which normally abuts the lower edge of tubular portion 75.

A relatively strong coil compression spring 91 is disposed between the cylinder 87 and the latch element 44' and sleeve 83.

In clip actuated operation, the lower portion 92 of the clip is pushed into the adjacent aperture 92' formed in the barrel section 76. This will pivot the clip 70 about the pivot point 78 and will force the beveled end 73 along the groove 89. This, in turn, will drive the cylinder 87 downwardly due to the wedging action of clip end 73. As the cylinder 87 moves downwardly, it will compress spring 91 and also carry the latch ball 37' downwardly relative to latch members 44' and 43', and into contact with said member 43', to thereby radially shift said ball in its groove 86. Release of inwardly directed pressure on clip portion 92 will allow member 87 to move upwardly again under the pressure of coil compression spring 91. Upward movement of member 87 will move upwardly the latch ball 37' relative to members 44' and 43'; and into contact with member 44' and into recess 93. At the same time, upward movement of member 87 will wedge the beveled end 73 outwardly and return the clip to the projecting position shown in FIGURE 6. With the latch ball 37' now seated in recess 93, spring 91 will be in a compressed condition and the distance from the lower

end of the cylinder 87 to the upper end of the sleeve 83 will now be shorter than before. The lower spring 67' will then raise the cartridge unit 29' upwardly so as to obtain the writing point 33' in a concealed position within hood 25'. A subsequent depression and release of the clip will project the writing point 33' and return the instrument to the position of FIGURE 6. It will be apparent from the foregoing and a comparison of FIGURE 6 with the embodiment of FIGURES 1 to 5, that the latch system 43', 44' and 37' of FIGURE 6 is essentially the same as the system 43, 44 and 37 of FIGURES 1 to 5 turned upside down. Also, FIGURE 6, like the embodiment of FIGURES 1 to 5, converts a transverse movement of the clip into a longitudinal movement to either move the ratchet toothed members relative to the locking ball (as in FIGURES 1 to 5) or move the locking ball relative to the ratchet toothed members (as in FIGURE 6). In either case, the operation is similar.

It will also be clear from the foregoing that the embodiment of FIGURES 6 to 8 can be tip-actuated in a manner similar to the tip-actuation of the embodiment of FIGURES 1 to 5.

FIGURES 9 to 14 represent still another embodiment of the invention, which can be clip-actuated or push-button actuated, and which also illustrates another type of latch mechanism. In this embodiment, tubular barrel sections 100 and 101 are joined by threaded connection with tubular connector 102. A cap 103 is fixed to the upper barrel section 100 and defines an aperture 104 through which extends the pushbutton 105. A clip 106 extends through the slot 107 defined in the side of said cap 103 and barrel section 100. A flat spring 108 has its upper hood end 109 embedded in cap 103, while its lower end 110 is bifurcated and bears against flange 111 defined by clip 106. The spring 108 urges said clip outwardly to an extended position where said flange 111 seats against the sides of barrel section 100 adjacent said slot 107. Integral with stem 105, is the cylinder 112 defining wedge surface 113 and the flat surface 114. The foot 115, of said cylinder, has a transverse semi-circular groove 116, which vents the ballpoint cartridge unit 117. The coil compression spring 118 maintains cartridge unit 117 in abutting engagement with foot 115. A semi-cylindrical latch receiver 119 is fixed to the sleeve 120, which in turn is fixed to tubular barrel section 100. The sleeve 120 also encompasses the semi-cylindrical portion of cylinder 112 defined by flat surface 114, and maintains the flat face 121 of latch receiver 119 in abutting engagement with the flat face 114. A heat shaped cam is defined by a groove 122 in flat face 121, which is shown in detail in FIGURE 13. A transversely extending groove 123, of semi-circular cross-section, is defined in face 114, and a locking ball 124 is carried within said grooves 122 and 123. Heart shaped cams are known per se, and have been described in various patents, e.g. U.S. Patents 2,671,354 and 2,972,980.

FIGURE 9 shows the writing instrument in a point retracted position with writing point 125 within the lower barrel section 101, and pushbutton stem 105 fully extended. The clip 106 can be pressed inwardly into the casing section 100, against the pressure of flat spring 108. The wedge 126, defined at the inner end of said clip, will thereby slide against the wedge surface 113 to wedge the cylinder 112 downwardly against pressure of coil compression spring 118. This downward movement of cylinder 112 will carry the latch ball 124 from the position indicated by *a* in FIGURE 13 to position *b* indicated by the dotted circle in said FIGURE 13. Upon release of inwardly directed manual pressure on clip 106, said clip will be returned to its outwardly projecting position by spring 108 and will disengage from wedge surface 113. This will allow cylinder 112 to move upwardly under the force of spring 118 transmitted through the cartridge 117 to the cylinder foot 115. This upward movement will carry ball 124 to a position *c* of FIGURE

13, and the instrument will assume the point projected position of FIGURE 10.

It will be apparent that upon again depressing the clip 106 into the casing, that wedging contact of said clip inner end 126 will again be made with wedge surface 113 to again drive the cylinder 112 downwardly. This downward movement will shift the latch ball 124 to position *d*. Release of this downward pressure, will allow the latch ball 124 to return to position *a* and again achieve the point retracted position of FIGURE 9.

From the foregoing it will be clear that the writing point can also be retracted and projected by depression and release of the pushbutton 105 since this also imparts longitudinal movement to cylinder 112 to thereby actuate the heart shaped cam mechanism in the aforesaid manner.

Still another embodiment of my invention is illustrated by FIGURES 15 and 16. This embodiment is a modification of that of FIGURES 9 to 14, with the following main differences: elimination of the pushbutton, a spring to urge the clip inwardly instead of outwardly, and changed proportions of several of the elements to permit use of a longer ballpoint cartridge. Specifically, the spring 108' bears inwardly against flange 111' to urge the clip 106' inwardly to always maintain wedge 126' in contact with wedge surface 113'. The cylinder 112' is formed with a bore 127 and air vent 128 for reception of the cartridge unit 117'. The abutting flat faces 114' and 121' are displaced closer to the clip side of the casing section 120' to thereby make room for said bore 127. The width of the grooves 122' and 123' in the embodiment of FIGURES 15 and 16 is somewhat more narrow than the corresponding grooves 122 and 123 in the embodiment of FIGURES 9 to 14.

Pressing the clip 106' into the casing as far as it will go, and then releasing said clip 106', will retract the writing point from its projected position of FIGURE 15 in the same manner described with regard to FIGURES 9 to 14. As the writing point is retracted, the cylinder 112' will be forced upwardly and will wedge the clip 106' outwardly against the pressure of spring 108'. The clip 106' will be thereby wedged to its fully extended clipping position where it can be passed over a shirt pocket. A subsequent depression and release of said clip 106' will return the writing point to its point projected position of FIGURE 15 and the clip 106' will remain partially within the casing in a non-clipping position. This insures against a user clipping the instrument in a pocket with its point projected, since the clip will not function as a pocket clip until the point is retracted. Another advantage of this construction is that with the point projected, the instrument will have a better balance since the clip is partially retracted within the casing.

In sum, the operation of the instrument of FIGURES 15 and 16 is similar to that of FIGURES 9 to 14 except for the above noted changes.

In conclusion, the present invention relates to a writing instrument having a side projection which can be depressed into the casing and then released to actuate the point. This side projection is preferably the pocket clip, although it will be apparent that a more simple pushbutton can be used for this purpose. This side projection is positively acting, that is the projection can always be pressed into the casing as far as it will go and then be released, and the writing point will be either retracted or projected. Thus, no control of pressure is required, instead just a simple pushing and release is all that is necessary. Also, the same location on the projection or clip can represent the pressing point both for retraction and projection.

This application is a continuation-in-part of my Serial Number 841,243, filed September 21, 1959, entitled "Writing Instrument," and now issued as U.S. Patent 3,051,132.

I claim:

1. A writing instrument comprising a tubular casing having a closed upper end and an open lower end; a ball-

point cartridge longitudinally movable within said casing between a point projected position and a point retracted position; a spring urging said ballpoint cartridge to a point retracted position; a clip unit extending through said casing proximate said upper end including a clipping portion disposed outside said casing and a wedge portion inside said casing; an actuator defining a wedge surface proximate its upper end for sliding wedging engagement with said wedge portion of said clip whereby transverse movement of said clip wedge portion is converted into longitudinal movement of said actuator; a ratchet latch receiver element having ratchet teeth defining a deep longitudinally extending recess and a shallow longitudinally extending recess; a latching pawl element, one of said elements being carried by said cartridge and the other of said elements being carried by said actuator, said latching pawl element being engageable with said ratchet teeth and shiftable back and forth between a position within said deep recess and a position within said shallow recess upon relative longitudinal movement of said latching pawl element and said latch receiver element obtained upon said longitudinal movement of said actuator, said latching pawl element when within one of said deep and shallow recesses being operable to obtain said cartridge in a point projected position against the pressure of said spring, said latching pawl element when within the other of said deep and said shallow recesses being operable to allow said cartridge to move to its point retracted position under the influence of said spring.

2. A writing instrument according to claim 1, wherein a sleeve within said casing engages said cartridge for conjoint longitudinal movement therewith, said sleeve defining an external annular groove, said pawl element being a latch ball carried within said groove, and said latch receiver element being carried by said actuator.

3. A writing instrument according to claim 2, wherein said casing includes a barrel and a hood, said hood defining the lower end of said casing and being longitudinally movable relative to said barrel whereby said relative longitudinal movement of said latching pawl element and said latch receiver element can also be obtained upon longitudinal movement of said cartridge upon the application and release of retractive force to said lower end of said casing.

4. A writing instrument according to claim 1, wherein said actuator includes a lower cylindrical portion defining an external annular groove, said pawl being a latch ball carried by said groove, and said latch receiver element is carried by said cartridge.

5. A writing instrument having a clip-actuated retractable writing point comprising: a casing having upper and lower ends; a writing unit including a writing point, said unit being mounted within said casing for longitudinal movement between a point projected position and a point retracted position; a clip unit extending through said casing having a clipping portion outside of said casing and an actuating portion inside said casing, said unit being mounted on said casing for substantially transverse movement of said actuating portion; a retraction-protraction mechanism engaging said writing unit including a latch element including a pawl and latch receiving element including ratchet teeth defining a deep longitudinally extending recess and a shallow longitudinally extending recess, said elements being shiftable relative one another between a first position wherein said pawl is within one of said deep and shallow recesses and a second position wherein said pawl is within the other of said deep and shallow recesses in response to longitudinal movement of one of said elements relative to the other of said elements, said elements when in said first position being operable to obtain said writing point in said point projected position, said elements when in said second position being operable to obtain said writing point in said point retracted position; and an actuator carrying one of said

elements for conjoint longitudinal movement, the other of said elements being carried by said writing unit, at least one of said actuator and said actuating portion of said clip unit defining a wedge surface, said actuator being in camming sliding engagement at said wedge surface with said actuating portion of said clip unit whereby transverse movement of said clip unit is converted into longitudinal movement of said actuator and element carried therewith to thereby shift said elements between said positions.

6. A writing instrument according to claim 5, wherein said casing comprises a tubular barrel having a lower end, and a tubular hood having upper and lower ends, said hood being carried by said barrel; and a spring within said barrel urging said hood to an extended position whereby the lower end of said hood extends through the lower end of said barrel, said writing unit when in said point projected position having its writing point extended through said hood lower end, said writing unit when in said point retracted position having its writing point retracted within said hood; said latch element and said latch receiving element also being shifted between said positions upon longitudinal movement of said writing unit obtained by the application and release of retractive force to said lower end of said hood and said writing point.

7. A writing instrument according to claim 5, wherein

said clip unit has an upper end pivotally mounted on said barrel.

8. A writing instrument according to claim 5, wherein said casing is provided with two transversely extending, longitudinally spaced slots, said clip unit having an upper portion extending through the uppermost of said slots and a lower end extendable into the lowermost of said slots, said slots serving as guides to insure the substantially transverse movement of said clip into said casing.
